UNITED STATES PATENT OFFICE.

OSCAR A. SPENCER, OF BLOOMER, WISCONSIN, ASSIGNOR OF TWO-THIRDS TO JOSEPH G. PRUEHER AND HAROLD E. McWITHEY.

SWITCHBOARD-PLUG.

1,004,306.

Specification of Letters Patent. Patented Sept. 26, 1911.

Application filed November 8, 1910. Serial No. 591,368.

To all whom it may concern:

Be it known that I, OSCAR A. SPENCER, citizen of the United States, residing at Bloomer, in the county of Chippewa and 5 State of Wisconsin, have invented certain new and useful Improvements in Switchboard-Plugs, of which the following is a specification.

This invention relates to improvements in 10 the plugs employed in telephone and similar switch boards, and has for one of its objects to simplify and improve the construction and increase the efficiency and utility of devices of this character.

15 Another object of the invention is to provide a simply constructed device of this character in which means are provided for firmly clamping the conductor wire to the body of the plug and likewise coupling the 20 plug tip thereto, the conductor and the tip being arranged for independent connection to the body of the plug.

Another object of the invention is to provide a device of this character whereby conductor wires of different sizes may be connected thereto without change in the structure, and also to permit the wire to be cut off and recoupled an indefinite number of 25 times without any change in the structure of 30 the device.

Another object of the invention is to provide a device of this character wherein all of the parts are readily accessible for adjustment, renewal, or repair.

35 With these and other objects in view the invention consists in certain novel features of construction as hereafter shown and described and then specifically pointed out in the claims; and, in the drawings illustrative 40 of the preferred embodiment of the invention, Figure 1 is a side elevation of the improved device, partly in section; Fig. 2 is a plan view of the same, partly in section; Fig. 3 is a longitudinal section on the line 45 3-3 of Fig. 2; Fig. 4 is a transverse section on the line 4-4 of Fig. 3; Fig. 5 is a rear elevation of the improved device with the conductor wire in transverse section on the line 5-5 of Fig. 1.

50 Corresponding and like parts are referred to in the following description and indicated in all the views of the drawings by the same reference characters.

The improved device comprises a hollow body formed in two sections, a main section

10 and a clamping section 11. The main section 10 is provided with a tip receiving socket 12 extending from one end and with the portion next to the socket cylindrical in outline, as shown at 14, and with sockets 15, 60 as shown. The member 11 conforms substantially in outline to the main portion 10, and bears thereon and thus completes the circle or produces a complete body substantially in circular form. The portion 11 of 65 the body is provided with tongues 16 at one end which conform to and are adapted to engage in the recesses 15 of the main body portion 10. The portion 11 is tapered or reduced in size toward the end opposite the 70 tongues 16 and is provided at the reduced end with a series of semi-circular grooves, indicated at 17, while the main body portion 10 is likewise provided with semi-circular grooves 18 which are located opposite 75 the grooves 17. The two sets of grooves form roughened or irregular surfaces which materially increase the grip and thus assist in holding the conductor "cord" in position.

The body portion 10 is provided with laterally directed ears 20, while the body portion 11 is provided with similar ears 21, the two sets of ears being located opposite each other and adapted to receive binding screws 22 by which the two parts 10-11 are firmly 80 coupled, and means likewise provided for applying a clamping strain upon the conductor cord. The ears 21, clamp screws 22, and the grooves 17-18 thus co-act to produce an effective clamp device which firmly 85 holds the cord in position and bears upon the insulation 19, and by reducing the size of the portion 11 at one end the latter is readily adjustable to cords of different sizes, as will be obvious, without change of structure of the device. The tongue 16 and the recesses 15 co-act to retain the two parts 10-11 firmly in coupled position. The portion 11 of the body is likewise provided with a relatively large opening 25, the object to 90 be hereafter explained.

The plug tip comprises a stem 26 for insertion into the socket 12 and with a barbed terminal 27 to engage in the contact members of the board in the usual manner. The 10 socket 12 is provided with a non-conducting sleeve of hard rubber or the like, and represented at 28, and located between the stem 26 and the socket 12, as shown in Fig. 3. The inner end of the stem 26 is threaded, as 1

shown at 29, and extends into the interior of the main portion 10 of the body, and engaging over the threaded portion of the stem within the body is a combined stop 5 and clamp member 30. Surrounding the stem 26 between the inner end of the insulating sleeve 28 and the stop member 30 is a stop ring 31 of suitable insulating material, such as hard rubber, and surrounding 10 the member 30 is another sleeve 32 of suitable insulating material. By this means the stem 26, with the barbed terminal 27, is firmly clamped within the body 10 and likewise effectually insulated therefrom. The 15 inner end of the member 30 is reduced as shown at 33 and provided with a binding screw 34 whereby the wire 19' is coupled to the member 30 and thence to the stem 26 and its barbed tip 27. The other wire 19" 20 is bent back between the insulation 19 and the member 10 or 11 as the case may be, and thus "contacts" with the body of the sleeve 12. The aperture 25 is so located that the binding screw 34 is accessible therethrough, 25 this being the function of the opening 25. Surrounding the body 10-11 when thus united is a protecting sleeve 36 of suitable insulating material, this outer sleeve being provided with recesses 37 for receiving the 30 ears 20-21, as shown.

The cords or conductors employed in connection with switch boards and like devices vary considerably in size, hence the advantage of providing a device which is adapted 35 to the different sizes of cords or wires without structural change therein, and by arranging the portion 11 of the body of reduced size at one end and arranging for clamping the two parts of the body together, the device is readily adapted to the various sizes of cords, as will be obvious. When a new cord or conductor wire is to be 40 inserted, or the device tightened upon a cord which has worked loose, the screws 22 are simply tightened with an ordinary screw 45 driver and without detaching any of the parts. The parts are readily dismembered when required, so that a worn or impaired portion may be replaced without discarding 50 the remainder of the device. If required the insulated sleeve 36 may be retained in position by a screw, represented at 35.

Switch board conductor wires or cords generally wear out at the shoulder of the plug from the continuous bending and twisting 55 occasioned by their use, and when this occurs the impaired wire is removed and severed and replaced by simply loosening the screws 22 and retightening them after the severed end of the cord is replaced between 60 the members 10-11.

The improved device may be constructed of any suitable material, but generally the two parts 10-11, the stem 26 with its barbed terminal 27, and the stop member 30 will 65 preferably be of brass, but may be of other material if required. The screws 22 and 34 are preferably of steel to insure greater durability.

Having thus described the invention, what 70 is claimed as new is:

1. A switch board plug comprising a hollow body divided into two parts longitudinally with one of the parts tapered toward one end, a casing inclosing said body, means 75 for detachably coupling said tapered body portion at its larger end to the other body portion, a plug tip between said body portions at said coupled ends, means for coupling one of the conductor wires to said 80 plug tip, and clamping means applied to the body portions at their smaller ends, whereby said body portions may be compressed upon the conductor cord without displacing the casing. 85

2. A switch board plug comprising a main body portion having a plug tip socket at one end and a half socket for a conductor wire at the other end, another body portion having an opening and with an opposing 90 half socket for a conductor wire at one end, means for compressing the body portions together to form a clamp for holding a conductor cord, a plug tip engaging said tip socket, a stop member engaging said plug 95 tip within the body, and a wire binding means carried by said stop and accessible through said opening.

In testimony whereof, I affix my signature in presence of two witnesses.

OSCAR A. SPENCER. [L. S.]
